UNITED STATES PATENT OFFICE

CHESTER H. CRITCHFIELD AND RUSSELL R. LOCKARD, OF MASSILLON, OHIO

DESIGN FOR A STAND

Application filed July 31, 1931. Serial No. 40,747. Term of patent 7 years.

To all whom it may concern:

Be it known that we, CHESTER H. CRITCHFIELD and RUSSELL R. LOCKARD, citizens of the United States, residing in Massillon, in the county of Stark and State of Ohio, have invented a new, original, and ornamental Design for a Stand, of which the following is a specification, reference being had to the accompanying drawing, forming part thereof.

The figure is a perspective view of a stand showing our new design.

What is claimed is:

The ornamental design for a stand, as shown.

CHESTER H. CRITCHFIELD.
RUSSELL R. LOCKARD.
